UNITED STATES PATENT OFFICE.

JOSEF BELTERMANN, OF MANNHEIM, GERMANY.

ABDOMINAL BANDAGE.

965,556.

Specification of Letters Patent. Patented July 26, 1910.

Application filed December 11, 1908. Serial No. 467,059.

To all whom it may concern:

Be it known that I, JOSEF BELTERMANN, a subject of the German Emperor, residing at D¹, No. 4, Mannheim, Baden, Germany, have invented a certain new and useful Improvement in Abdominal Bandages, of which the following is a specification.

My invention relates to belly - bandages for stout persons especially pregnant women. 10 The new bandage consists essentially of a non-elastic main portion of washable material corresponding to the contour of the person's body, and elastic stays detachably secured to the main portion and adapted 15 to raise the belly and thus to support the enervated muscles of the belly.

In the accompanying drawing is shown a constructional form of the object of my invention.

20 a is the main portion of the bandage, b are the elastic stays. The latter consist of several parallel indiarubber-bands which are connected at both ends to common flaps b¹ provided with button-holes. The stays b 25 are detachably secured to the main portion a by means of a lace c which is passed through eyes d provided in the main portion a and around the separate bands of the stays b. The main portion a has connected 30 to its ends two closing straps e and f provided with button-holes, and is itself provided with buttons g and h. After the main portion a has been put around the body of the person, the closing straps e and f are 35 crossed over the back by drawing the strap e through the strap f and then attaching both straps to the buttons g. The end-flaps b¹ of the stays b are then also attached to the buttons h; for this purpose the stays b must 40 be slightly stretched so that the necessary tension is obtained.

It is a great advantage to place the main portion a of the bandage in position without subjecting the same to tension and to 45 give it the necessary tension by stretching

the elastic stays and attaching their ends to the main portion. The detachability of the elastic stays permits of them being easily exchanged and also a thorough cleaning of the main portion without any effect 50 on the stays.

The indiarubber-bands being elastic each in itself and independent of each other, the stays b are adapted to accommodate exactly to the whole belly with the necessary pressure according to the different muscles of 55 the belly.

The bandage may be provided also with an elastic detachable back buckle of celluloid or the like for straightening purposes. 60

What I claim as my invention and desire to secure by Letters Patent is:—

In an abdominal bandage the combination of a main portion of washable material, detachable stays consisting of several parallel 65 indiarubber-bands which are elastic each in itself and independent of each other and connected at both ends to common flaps, means for detachably securing the said bands to the main portion consisting of a 70 lace passed through eyes provided in the main portion and around the separate bands, means for attaching the end flaps of the stays to the main portion consisting of buttons provided on the main portion and engaging with button-holes provided in said straps. 75

In testimony whereof I have hereunto signed my name to this specification in the presence of two subscribing witnesses.

JOSEF BELTERMANN.
